UNITED STATES PATENT OFFICE.

LOUIS D'ELIA, OF ATLANTIC CITY, NEW JERSEY.

LIFE-PRESERVING APPARATUS.

1,113,418.

Specification of Letters Patent. Patented Oct. 13, 1914.

Application filed September 9, 1913. Serial No. 788,781.

To all whom it may concern:

Be it known that I, Louis D'ELIA, a citizen of the United States, residing at Atlantic City, in the county of Atlantic, State 5 of New Jersey, have invented a new and useful Life-Preserving Apparatus, of which the following is a specification.

My invention consists of a life preserving apparatus embodying the following features, a water proof garment, a helmet, which is connectible with said garment, and which is provided with means for admitting air to the person occupying the apparatus, means for discharging water that may 10 enter the helmet, means for preventing a large volume of water that may enter the helmet from flooding the person, means for sustaining the helmet on the head of the person, means for widening the upper portion 15 of the garment to readily admit the person thereinto, means for providing an illuminator or light for distinguishing purposes especially at night, means for controlling said light by the hand of the occupant 20 of the garment within the sleeve of the latter, and a life preserver adapted to be placed on the body of the person and guarded from improper shifting in upwardly or downwardly direction.

It consists further of details of construction as will be described.

The invention is satisfactorily illustrated in the accompanying drawing, but the important instrumentalities thereof may be 35 varied, and so it is to be understood that the invention is not limited to the specific arrangement and organization shown and described.

Figure 1 represents a perspective view of 40 a life saving apparatus embodying my invention. Fig. 2 represents a vertical section of the upper portion thereof. Fig. 3 represents a plan view of a ring member employed. Fig. 4 represents a horizontal section of said member, the portion of the garment attached thereto, and the clamping means for the flap of said garment. Fig. 5 represents a top view of the sustaining cap of the apparatus. Fig. 6 represents a side 50 elevation of the upper portion of the garment and parts connected therewith. Fig. 7 represents a rear view of the life preserver employed, and means for sustaining the

same against upward and downward shifting.

55

Similar numerals of reference indicate corresponding parts in the figures.

Referring to the drawings: 1 designates what I term as a helmet of the apparatus. It consists of a crown and brim of the conventional form of a hat having within said crown the wall 2 which rises from the base of said crown and extends under the top of the same and is separated therefrom forming the chamber 3 which is closed at the bottom and in communication with the atmosphere by the openings or ports 4 in the side and top of the crown, said chamber being open at the top forming the port 5, whereby the air entering said chamber may 60 70 pass from the latter into the interior of the crown so as to supply the same with the air for use of the person occupying the apparatus.

On the underside of the top of the wall 75 2 is the valve 6, which is adapted to close the port 5 when so required, said valve being suspended on the bolts 7 which pass freely through said valve and are secured to said wall. Interposed between the valve 80 and the heads of the bolts 7 are the springs 8 whose tendency is to raise the valve and close against the wall 2 around the port 5 as the seat of said valve. In order to open the valve, it is adapted on its upper side to 85 be engaged by the cam or crank member 9, which is formed with or attached to the rod 10, whose bearings are on the side of the crown of the helmet, it being seen that when the rod is turned by a suitable handle 90 thereon, so as to place the cam or crank member 9 in the position shown in Fig. 2, it depresses the valve and so removes it from its seat and uncovers the port 5, whereby air admitted into the chamber 3, may 95 pass through the wall 2 of the helmet for the purpose stated above.

11 designate hangers which are secured to and depend from the wall 2 and connected on their lower ends with the annular 100 rim, forming within the helmet a cap which is adapted to be fitted on the head of the person wearing or occupying the apparatus and retained thereon by the straps 13 which have passed under the chin of said 105 person and suitably secured. On the under-

side of the brim of the helmet is the divisional ring 14, the sections of which are connected by the hinge 15, whereby the ring may be opened and closed, for purposes to be hereinafter explained. On the underside of the sections of said ring is the flange 16 to which is secured the upper end of the main portion of the neck 17 of the garment 18 employed, it being noticed that said 10 neck is divided in front, and extended forward of the ring forming the flap 19 which when the ring is opened separates, thus increasing the width of said neck, providing a greater facility for the limbs and body of 15 the wearer to enter said neck and so occupy the body, legs and arms of the garment, it being noticed that said garment is made of water-proof material, and that when the ring 14, and consequently the neck 17 is 20 closed, water is prevented from entering the garment, attention being directed to the fact that the side members of the flap are brought together and tightly closed between the bars 20, with which are pivoted the clips 21, 25 which are adapted to clasp said bars and so compress the latter against said flap whereby the top of the flap primarily opened is closed, so that water is prevented from entering said top and filling the garment 30 therewith.

The helmet is placed on the ring 14 and connected therewith by the bolts 22 and cams 23 thereon, the heads of the bolts and the cams bearing respectively against the under- 35 side of the flange 16 and the upper side of the brim of the helmet or hat, it being evident that when the cams are properly turned the helmet the ring and flange, and consequently the neck of the garment are firmly 40 connected and held together, and a packing 24 is interposed between said parts and a tight joint is provided which prevents water from passing between said members. Then the cap 12 is rested on the head of the occupant, whereby the helmet is held in place 45 and the garment supported from the helmet.

25 designates a life preserver of the form of a float which is formed of buoyant material adapted to be placed around the body 50 of the occupant of the apparatus and provided with shoulder straps 26 for sustaining the same in position. This is assisted by straps 27 which are connected with the cap 12, and the upper portion of said life 55 preserver 25, so that the latter is prevented from shifting downwardly. Then in order to prevent the upward shifting of said life preserver, it is connected as at 28 with the body belt 29, the latter being worn by the 60 person, the effect of which is evident.

On the front of the neck 17 on opposite sides of the flap 19 are openings covered by transparent material forming the windows 30 which are located in line or adjacent to the eyes of the person within the ap-

paratus, whereby the person may see through said windows so as to guide or direct him in his movement through the water. Secured to the crown of the helmet is the lens bull's eye lantern or head-light 31 70 which is illuminated by an electric lamp, the latter being in communication with the battery 32 by means of suitable conductors 33, and having connected with it the conductor 34 which is provided on its lower end with the push-button 35 whereby a current may be supplied to said lamp and thus illuminating the light 31, and providing the helmet with a light, a matter of use especially in the darkness of night. The conductor 34 extends from said lamp into the sleeve of the garment to near the lower end thereof or glove thereon, so that said push button 35 is within convenient reach of the hand of the wearer of the garment. The 80 top of the cap is provided with strips or pads 36 to cause the cap to set easy on the head while being subjected to the weight of the helmet, garment and connected parts.

The garment is sufficiently large to place 90 food and drinking water therein, it being evident that the hands of the person are sufficiently free to reach the same and convey them to the mouth of the person.

The operation is as follows: The helmet 95 is removed from the ring 14 and the latter opened, when the person enters the garment. Then the flap 19 is closed and secured, and the ring 14 also closed and secured by a latch or other suitable means. The helmet is now placed in position on the ring and the cap fitted on the head of the person. The helmet is then clamped to said ring, when the person may enter the water, the apparatus sinking to a safe extent below the windows 30, leaving the legs of the person free to tread the water, and the arms free to guide him in his movements, the garment being filled with air which assists in supplying the person with the same for 100 breathing purposes through the openings 4, and port 5 in the helmet. Water that may dash through the top openings 4 will enter the chamber 3 and escape therefrom through the side ports 4. Should the water be rough 105 and there is apparent liability of its entering said chamber in a volume or extent whereby it might pass through the port 5 and so flood the neck 17 and reach the nose and mouth of the person and jeopardize the same while also filling the garment, the person can operate the cam 9 whereby it turns from the valve 6 and relieves the valve 6 when the latter under the action of the spring 8 closes on its seat and so prevents the passage of water through said port. The person, however, watches the water through the windows 30 and at proper times, operates the cam to cause the valve 110 to open when the person is further supplied 115

with fresh air from the chamber 3 through the openings 4 and port 5, thus sustaining the life of the person. When the helmet is removed, the ring may be opened and the flap relieved when the garment may be removed from the person or vice versa.

Having thus described my invention what I claim as new and desire to secure by Letters Patent, is:—

10 1. In a life saving apparatus, a helmet having an air and water intake in a wall thereof, and a chamber within the crown in communication with said intake and the interior of said crown, said intake being also 15 adapted as a discharge for the water admitted into said chamber.

2. In a life saving apparatus, a helmet having a chamber within the same, an air intake in the wall of said helmet in communication with said chamber, and a port in 20 said chamber forming a communication for the latter with the interior of said helmet.

3. In a life saving apparatus, a helmet having a chamber within the same, an air 25 and water intake in a wall of said helmet in communication with said chamber, a port in said chamber forming a communication for the latter with the interior of said helmet, and a valve in the helmet adapted to open 30 and close said port.

4. In a life saving apparatus, a helmet having a chamber within the same, an air and water intake in a wall of said helmet in communication with said chamber, a port in 35 said chamber forming a communication for the latter with the interior of said helmet, a valve in the helmet adapted to open and close said port, and means on the helmet for operating said valve in opposite directions.

40 5. In a life saving apparatus, a helmet having an air and water receiving chamber therein, a port in said chamber adapted to form a communication between the latter and the interior of the helmet, a cam member 45 in the helmet adapted to bear against one face of said valve, a resilient member in the

helmet adapted to bear against the other face of said valve, and means for supporting said members.

6. In a life saving apparatus, a helmet, a divided ring adapted to be fitted on the brim of said helmet, a water tight garment adapted to be suspended from said ring and connected therewith, and means for clamping said ring to said brim. 55

7. In a life saving apparatus, a helmet, a divided ring adapted to be connected with said helmet, a garment adapted to be connected with said ring, the neck portion of said garment having an expansible flap on 60 said garment, and means for closing and clamping said flap.

8. In a life preserving apparatus, a helmet, an electrically operated headlight therein, a garment with which said helmet is connected, a battery, an electric conductor extending from said battery to said light, said light being in the electric circuit, an electric conductor extending from said light, the sleeve of said garment containing the same, 70 and means on the lower terminal of the latter named conductor within reach of the hand of the occupant of the garment when the latter is on the body for turning on and cutting off the current to and from said 75 light.

9. In a life preserving apparatus, a helmet, a life preserver proper adapted to be fitted on the body of the occupant, a cap in 80 said helmet adapted to be rested on the head of the occupant of said apparatus, means connecting said cap with said life preserver for preventing downward displacement of said life preserver proper, a body belt, and means connecting the said belt with said life 85 preserver proper for preventing upward displacement of the latter.
